C. L. NICHOLS.
LINE CUTTING TOOL.
APPLICATION FILED SEPT. 10, 1919.

1,325,901.

Patented Dec. 23, 1919.

UNITED STATES PATENT OFFICE.

CLARENCE LAMONT NICHOLS, OF RAVENSWOOD, WEST VIRGINIA.

LINE-CUTTING TOOL.

1,325,901.

Specification of Letters Patent. Patented Dec. 23, 1919.

Application filed September 10, 1919. Serial No. 322,907.

To all whom it may concern:

Be it known that I, CLARENCE L. NICHOLS, a citizen of the United States, and a resident of Ravenswood, in the county of Jackson 5 and State of West Virginia, have made certain new and useful Improvements in Line-Cutting Tools, of which the following is a specification.

My invention relates to a line cutting tool 10 such as is adapted to be used in severing drill connections and the like which have become lodged in a well or boring.

The purpose of my invention is the provision of a line cutting tool having cutting 15 means which is operable automatically to cut a drill controlling line when the tool engages the drill, such means being normally inactive to prevent the accidental cutting of the line during manipulation of the tool to 20 and from the drill.

I will describe one form of cutting tool embodying my invention and will then point out the novel features thereof in claims.

In the accompanying drawings:

25 Figure 1 is a view showing in side elevation one form of cutting tool embodying my invention with the cover plate removed;

Fig. 2 is a vertical sectional view taken on the line 2—2 of Fig. 1;

30 Fig. 3 is a detailed perspective view of the gripping jaw shown in Figs. 1 and 2;

Fig. 4 is a perspective view of the cutting jaw shown in Figs. 1 and 2.

Similar reference characters refer to similar parts in each of the several views.

Referring specifically to the drawings, A designates the body of the tool, the upper end of which is tapered as at 15 and provided at its apex with a threaded extension 16 to which a controlling line or rod may be connected. At one side of the body A, I provide a line way 17 for receiving a line such as a wire or rope (not shown), for actuating the drill within a well. The line-way 17 extends upwardly through the tapered portion 15, as shown in Fig. 2, and terminates at one side of the extension 16, so that the tool may be moved upon the drill line without interfering with the controlling line 45 connected to the extension 16. On the same side as the line-way 17, the body A is formed with a pocket 18 in which is mounted a gripping jaw 19. One wall of the pocket 18 is inclined toward the lower end of the line-way 17 as at 20, while that face of the gripping jaw which contacts with the inclined

wall is also inclined in the direction of the line-way so that when the latter moves downwardly within the pocket, it will restrict the line-way at this point to effect a gripping 60 of the line, as will be understood. For maintaining the gripping jaw in contact with the inclined wall 20, I provide a rib 21 which as shown in Fig. 3, extends along the inclined edge of the jaw and works within a slot 22 65 formed in one side wall of the slot 18. The front edge of the gripping jaw 20 is formed with a series of teeth 19^a which project upwardly, as shown for a purpose to be herein-after described. Upon the opposite side of 70 the line-way 17, the body A is formed with a pocket 23 having oppositely inclined upper and lower walls which are connected by the rounded wall 24. The wall 24 acts as a bearing for the rounded portion of the 75 rounded end of a cutting jaw 25, and this jaw 25 is confined within this portion of the pocket by means of a pin 26, which as shown in Fig. 4, extends laterally from one side of the jaw. The outer end of the jaw 25 is 80 sharpened to provide a cutting edge 27. As shown in Fig. 2, the pockets 18 and 23 as well as a part of the line-way 17 are closed by a cover plate K secured at suitable points by screws. 85

As shown in dotted lines in Fig. 1, the upper walls of the pockets 18 and 23 are recessed to receive coil retractile springs 28 and 29 which are secured therein by means of pins 30. The lower ends of the springs 90 28 and 29 encircle lugs 31 and 32 formed on the jaws 25 and 19, respectively, and serve to bias the jaws to the positions indicated in dash lines in Fig. 1.

As illustrated to advantage in Fig. 2, the 95 lower end of the body A is recessed to provide a chamber C in which works an operating rod R actuating the locking plate P. The plate P is mounted for sliding movement within a slot 33, which forms a communication between the chamber C and the front side of the body A. As shown in Fig. 1, the front edge of the plate P is recessed centrally thereof to accommodate a line mounted in the line-way 17. As shown 100 in Fig. 2, the plate P is formed with a slot 34 in which works the rod R, such rod being bent longitudinally to provide a cam K' which projects and retracts the locking plate P into and out of the line-way 17, according as the rod occupies one extreme 105 position or the other. When in this po-

sition plate P rests within recesses 35 and 36 formed in the jaws 25 and 19 respectively, thus locking the latter against movement under the action of the springs 28 and 29. 5 The lower end of rod R is formed with a circular portion 37, which has a sliding fit within the chamber C to actuate and guide the rod R in actuating the plate P. The movement of the rod R by the portion 37 10 is limited by virtue of a pin 38 working within a slot 39 formed in the portion 37, it being understood that the pin 38 engages one end or the other of the slot 39, according as the rod R is in one extreme position 15 or the other.

In the operation of the cutting tool, it is lowered until it engages the upper end of the drill or drill socket. With the movable parts of the tool in their normal or set position, as shown in Fig. 1, the jaws 19 and 20 25 do not engage the line as they are locked in set position by means of the plate P. In this position of the plate P the portion 37 projects beyond the lower end of the 25 body A so that when the tool engages the drill, the portion 37 is moved upwardly, thus actuating the rod R and retracting the plate P from the recesses 35 and 36. As soon as this occurs the gripping jaw 25 moves 30 downwardly to the dotted line position shown in Fig. 1 under the action of its spring 29. In this position, the jaw 19 forces the line toward the cutting edge of the jaw 25. In the meantime the jaw 25 35 moves to the dotted line position under the action of the spring 28, thereby causing the cutting edge 27 to engage the line. With the jaws in this position, the entire tool is now slightly elevated on the line so that the teeth 19^a of the gripping jaw 19 engage the line and force the jaw to the lowermost position within the pocket 18. This causes the line to be forced into engagement with the cutting edge 27 and because of the manner 40 in which the jaw 25 is pivotally mounted, the latter also swings downwardly simultaneously with the jaw 19, thus causing the two to coact to sever the line. After the line 45 has been severed the tool may be readily withdrawn from the well.

Although I have herein shown and described only one form of cutting tool embodying my invention, it is to be understood that various changes and modifications may 55 be made herein without departing from the spirit of the invention and the spirit and scope of the appended claims.

Having described my invention, what I claim is:—

60 1. A line cutting tool, comprising a body formed with a line-way, a pair of pockets on opposite sides of the line-way, a gripping jaw in one of said pockets, surfaces on the

body and one wall of the corresponding pocket, inclined toward the line-way, a cutting jaw pivoted to the other pocket for movement in the direction of the line-way, means for biasing the jaws downwardly to the line-way, a locking plate slidable transversely of the line-way and adapted to engage the jaws for locking the same in retracted position against the action of said biasing means, an operating pin bent to provide a cam which is slidable to engage the locking plate for moving the latter out 75 of engagement with the jaws.

2. A line tool, comprising a body, having a line-way formed therein, a gripping jaw slidably mounted in the body and biased toward the line-way, a cutting jaw pivotally mounted on the body and biased toward the line-way, and means for locking the jaws in a position against the action of their bias.

3. A line cutting tool, comprising a body having a line-way formed therein, a slidable gripping jaw, a pivoted cutting jaw, said jaws being mounted within the body upon opposite sides of said line-way and biased toward the latter, and means for locking the jaws in a position against the action of their bias comprising a slidable plate adapted to engage the jaws, and means projecting from the lower end of said body for retracting said plate.

4. A line cutting tool, comprising a body having a line-way formed therein, a gripping jaw, a cutting jaw, said jaws being mounted in the body and biased toward the line-way, means for locking the jaws in a position against the action of their bias comprising a plate slidable in the body, and a rod bent to provide a cam which is engageable with said plate to move the latter into and out of engagement with said jaws.

5. A line cutting tool, comprising a body having a line-way formed therein, a slidable jaw on one side of the line-way, said jaw and body having inclined surfaces for moving the jaw toward the line-way when the same is moved downwardly, a cutting jaw pivoted in the body upon the opposite side of the line-way, springs for biasing the jaws downwardly toward the line-way, recesses formed in the jaws, a slidable plate adapted to rest in said recesses for holding the jaws against the tension of said spring, and a rod slidable through said plate and having a cam formed thereon for actuating the latter, said rod projecting from the lower end of said body.

CLARENCE LAMONT NICHOLS.
